FIG. 5.

UNITED STATES PATENT OFFICE

OTTO H. HARTMANN, OF KASSEL-WILHELMSHÖHE, GERMANY, ASSIGNEE TO SCHMIDT'SCHE HEISSDAMPF-GESELLSCHAFT MIT BESCHRÄNKTER HAFTUNG, OF KASSEL-WILHELMSHÖHE, GERMANY

MULTIPRESSURE BOILER INSTALLATION

Application filed June 5, 1928, Serial No. 283,054, and in Germany June 28, 1927.

My invention relates to methods of and apparatus for operating steam-boiler installations with two or more working pressures.

Experience of such installations has shown that after only a comparatively short time, for example, a quarter of an hour in the case of a two-pressure locomotive boiler, the high-pressure section has attained approximately its full pressure, the heating up of the water and of the boiler itself in the lower-pressure section taking considerably more time. In the high-pressure section, therefore, steam of very high pressure is available comparatively soon, but in most cases cannot be effectively utilized.

The object of the present invention is to overcome this disadvantage.

With such an object, according to the present invention, during the heating up of a boiler installation of the kind in question, steam as it is generated in a high-pressure section is led through a superheater or superheaters and thence to the water space of a lower-pressure section of the boiler installation.

The high-pressure steam may be passed either through the superheater of only a high-pressure section or in series or parallel through all the superheaters. In general, the first method of working is preferable when the superheater of a high-pressure section lies in the hottest zone of the flue gases, and the superheaters of the next-following pressure sections lie in zones in which the flue gases have already been more or less reduced in temperature, while the other methods of working are to be preferred when all the superheaters are arranged in the same zone of the flue gases as near as possible to the furnace.

By virtue of my present invention, it becomes possible to heat up the lower-pressure sections of the boiler installation more rapidly, so that the time taken in heating up the whole boiler installation is substantially reduced.

It is a further advantage of my invention that the superheater tubes can be kept cool owing to the steam passing through them during the heating-up period.

Finally, heat stresses otherwise occurring while heating up the lower-pressure boilers owing to layers of water at different temperatures, are avoided and the life of the boilers is thus increased.

My invention is applicable with equal advantage both to stationary and to portable boiler installations and also to the direct and indirect generation of steam.

In the accompanying drawings, which show certain constructional forms of the invention by way of example:

Figure 1 is a longitudinal section of a two-pressure marine boiler,

Figure 2 is a cross section on the line II—II of Figure 1,

Figures 3 and 4 show two specific arrangements of the superheater connections; and

Figure 5 is a longitudinal section through a two-pressure locomotive.

In the two-pressure marine boiler shown in Figures 1 and 2, the high-pressure section generates steam indirectly by means of a heat carrier circulating in a closed cycle. Instead of the usual furnace flue, a tube system, 1, is provided which is connected at its ends to upper distributor headers, 2, and to lower collector headers, 3, and serves to heat the heat carrier, for example, water or some other suitable fluid. The heat carrier heated in the tube system, 1, is led from the upper distributor headers, 2, through the riser tubes, 4, to the serpentines or like heating elements, 6, arranged in the upper drum, 5, where the high-pressure working steam is generated; here the heat carrier gives up its heat to the water surrounding the serpentines and then flows through the downcomer tubes, 7, to the lower collector headers, 3, in order thence to repeat its circulation through the tube system.

The low-pressure part of the boiler installation is constructed as a smoke-tube boiler, 8.

A high-pressure superheater, 9, and a low-pressure superheater, 10, are arranged in the reversing chamber, 28, of the installation. The steam from the high-pressure drum, 5, passes through the pipe, 11, controlled by a shut-off valve, 12, into the superheater, 9, from which the superheated steam is led

through the pipe, 13, provided with a valve, 14, to the engine or elsewhere. The low-pressure steam passes from the boiler, 8, through the pipe, 15, controlled by a shut-off valve, 16, into the superheater, 10, and thence in the superheated condition through the pipe, 17, fitted with a valve, 18, to its destination. From the delivery pipe, 13, of the high-pressure superheater, 9, the pipe, 19, leads to the water space of the low-pressure boiler, 8, this pipe being provided at its two ends with the valves, 20 and 21, respectively.

During the heating up of the boiler installation, the valves, 14, 16 and 18, are closed while the valves, 12, 20 and 21, are open. In the high-pressure section of the installation, steam is generated in a comparatively short time and is led from the drum, 5, through the open valve, 12, and pipe, 11, to the high-pressure superheater, 9, from which the superheated steam passes by way of the pipe, 19, and the open valves, 20 and 21, and is blown into the water space of the low-pressure boiler, 8.

It will be seen without further description that in this way the low-pressure boiler, 8, reaches its full working pressure in a considerably shorter time than heretofore and consequently the time required for heating up the whole installation is substantially reduced.

The valves, 20 and 21, may either be opened and shut by hand, or they may be of the automatic type responsive to the pressure or temperature conditions in the high- and low-pressure boilers in a well known manner; for example, the valves may open on the attainment of a predetermined pressure in the high-pressure boiler and close when the full working pressure in the low-pressure boiler is reached.

It will be obvious that my invention can also be applied to boiler installations in which the steam is directly generated in the high-pressure section or indirectly generated in the low-pressure section, and also to installations having more than two boiler sections working at different pressures.

As pointed out above, in addition to the reduced time taken in heating up, the superheater tubes are efficiently cooled by the steam passing through them.

If the superheaters of the different pressure sections lie in the same temperature zone of the flue gases and particularly in the case where they lie as close as possible to the furnace, it is preferable when raising steam to pass the high-pressure steam through the superheaters of all the pressure stages as shown, for example, in Figures 3 and 4.

In the example according to Figure 3, in order to pass the steam in series through the superheaters, 9 and 10, a connecting pipe, 22, fitted with a shut-off valve, 23, is provided between the superheated-steam delivery pipe,

13, from the high-pressure superheater, 9, and the steam pipe, 15, to the low-pressure superheater, 10.

In the example according to Figure 4, the steam from the high-pressure boiler, on the other hand, passes through the two superheaters, 9 and 10, in parallel. This is effected by a connecting pipe, 24, with shut-off valve, 25, between the steam inlet pipe, 11, to the high-pressure superheater, 9, and the steam inlet pipe, 15, to the low-pressure superheater, 10. In addition, the pipe, 19, with valve, 20, from the superheated-steam delivery pipe, 13, of the high-pressure superheater, 9, to the low-pressure boiler, 8, is connected by the pipe, 26, fitted with shut-off valve, 27, to the superheated-steam delivery pipe, 17, from the low-pressure superheater 10.

Figure 5 shows the application of the invention to a two-pressure boiler system for locomotives, in which the low-pressure section, 8, is constructed as a longitudinal boiler in the usual way while the fire-box, 29, forms the high-pressure section of the installation, the walls of this high-pressure fire-box constituting the tube system, 1, of the heat carrier, which generates the high-pressure working steam in the upper drum, 5, as described above with respect to Figures 1 and 2.

The same reference symbols are used to denote corresponding parts in Figures 1 and 5. In the locomotive shown in Figure 5 the high-pressure superheater, 9, and the low-pressure superheater, 10, are arranged in the smoke-tube boiler, 8. The delivery pipe, 13, of the high-pressure superheater leads to the high-pressure cylinder, 30. The exhaust steam from the high-pressure cylinder, 30, passes through a pipe, 32, to a container, 33, where it is mixed with the superheated low-pressure steam coming through the pipe, 17, from the superheater, 10. This steam mixture is led through a pipe, 34, to the low-pressure cylinder, 31, from which it passes through the conduit, 35, to the blast pipe, 36. The numeral, 37, indicates a feed water pump which takes a portion of the water contained in the low-pressure boiler, 8, through a pipe, 38, and delivers such water as feed water to the high-pressure drum, 5, through a conduit, 39.

I declare that what I claim is:—

1. Method of initially heating up multi-pressure boiler installations having superheating devices for superheating the steam generated in the respective pressure sections of the boiler, which consists in leading steam generated in a high-pressure section of the boiler installation through a superheater heated by the same furnace as the boiler itself and thence to the water space of a low-pressure section of the boiler installation.

2. Method of initially heating up multi-pressure boiler installations having super-

heating devices for superheating the steam generated in the respective pressure sections of the boiler, which consists in simultaneously supplying heat to at least two pressure sections of the boiler, and leading steam generated in a high-pressure section of the boiler installation through a superheater heated by the same furnace as the boiler itself and thence to the water space of a low-pressure section of the boiler installation.

10 3. Method as set forth in claim 1 wherein steam from a high-pressure section is led through the superheaters of all the pressure stages.

15 4. In combination with a multi-pressure boiler installation having superheating devices for superheating the steam generated in the respective pressure sections of the boiler installation, a delivery pipe leading from a high-pressure superheater heated by the same furnace as the boiler itself, and means for conducting steam from said high-pressure superheater to a low-pressure section of the boiler installation.

20 5. In combination with a multi-pressure boiler installation having superheating devices for superheating the steam generated in the respective pressure sections of the boiler installation, means for conducting steam from said superheating devices to a low-pressure section of the boiler installation.

25 6. In combination with a multi-pressure boiler installation having superheating devices for superheating the steam generated in the respective pressure sections of the boiler installation, delivery pipes leading from said superheating devices, and at least one conduit provided with shut-off valves leading from a delivery pipe to the water space of a low-pressure section of the boiler installation.

30 7. In combination with a multi-pressure steam plant having superheating devices for superheating the steam produced in the respective pressure sections of the boiler installation, a delivery pipe leading from a high-pressure superheater, a steam inlet pipe between said high-pressure superheater and a high-pressure boiler, a low-pressure steam inlet pipe to a low-pressure superheater, a low-pressure steam delivering pipe from said superheater, a connecting pipe between said high-pressure delivery pipe and said low-pressure inlet pipe, a shut-off valve in said connecting pipe, and a branch pipe provided with shut-off valves leading from said low pressure delivery pipe to the water space of a low-pressure boiler.

35 60 In testimony whereof I affix my signature.
OTTO H. HARTMANN.
